UNITED STATES PATENT OFFICE

DANIEL N. HYMAN, OF DETROIT, MICHIGAN

COVER FOR BUSES

Application filed March 8, 1926. Serial No. 93,199.

This invention relates generally to vehicle covers and refers more particularly to covers for open aisles on the upper decks of motor buses and the like.

5 One of the essential objects of the invention is to provide a cover of this type that may be mounted on the usual upper deck top sections of the bus for protecting passengers beneath the top sections from the weather

10 elements.

Another object is to provide a cover of the character described that may be readily collapsed upon the deck top sections to enable buses equipped with said covers to pass free-

15 ly under low viaducts, bridges and the like.

A further object is to provide a strong and durable cover that is simple in construction and can be manufactured at a comparatively low cost.

20 With the above and other objects in view, the invention resides in certain novel features of construction, combinations and arrangements of parts as will be more fully described and particularly pointed out in the appended claims.

In the accompanying drawings:

Figure 1 is a fragmentary perspective view of a motor bus with a cover embodying my invention mounted thereon.

30 Figure 2 is a perspective view of the motor bus under a viaduct and showing the cover collapsed.

Figure 3 is a sectional view taken on the line 3—3 of Figure 4.

35 Figure 4 is a fragmentary vertical sectional view through one of the top sections and cover.

Figure 5 is a top plan view of the main supporting frame mounted upon the top sections of the bus.

40 Figure 6 is a fragmentary side elevation of the rear end construction of one top section and the cover actuating means when in raised position.

Figure 7 is a view similar to Figure 6 but showing the cover in lowered position.

45 Figure 8 is a fragmentary perspective view of the rear end of the bus top sections with the supporting frame mounted thereon.

Figure 9 is a fragmentary side elevation of a portion of the supporting frame.

Figure 10 is a view similar to Figure 9, but showing the bow in lowered position.

Figure 11 is a detail perspective view of one of the brackets.

Figure 12 is a detail perspective view of one of the socket members.

Figure 13 is a vertical sectional view taken on the line 12—12 of Figure 4.

Figure 14 is a fragmentary sectional view through the auxiliary spring retaining means.

Referring now to the drawings, the numeral 1 designates a motor bus having an upper deck 2 upon which suitable seats (not shown) and the top sections 4 and 5 respectively are mounted. As usual, the seats (not shown) are arranged in rows at each side of the deck, while the top sections 4 and 5 extend longitudinally of the bus over the seats and are preferably substantially equal in width to the width of the seats, hence a suitable aisle 6 is provided on the deck for the conductor and passengers.

Heretofore such aisles have been uncovered to permit such buses to pass beneath viaducts and bridges and the like, warning being given by the conductor to passengers to remain seated beneath the top sections 4 and 5 while the bus is passing beneath such viaducts etc. However it has been found that the top sections 4 and 5 respectively alone were insufficient to afford the proper protection to passengers on the upper deck during inclement weather. For instance rain, snow and etc. would fall through the space provided by the open aisle onto the seats and passengers.

With the present invention the objectionable features just referred to have been overcome entirely by the provision of an inverted trough-shaped cover 7 that is mounted above the aisle 6 on the adjacent longitudinal edge portions of the top sections 4 and 5. As shown, this cover 7 has a collapsible frame 8 which comprises a pair of substantially flat attaching bars 9 that are rigidly secured to the top sections 4 and 5 adjacent to the inner longitudinal edge portions thereof, and a

series of inverted U-shaped bows 10 that are pivotally mounted upon said bars 9. As shown, elongated brackets 11 are rigidly secured to the bars 9 at spaced points thereof and are provided at their rear ends with the upstanding lugs 12, while the lower ends of the bows 10 are secured in socket members 13 which in turn are pivotally connected to the upstanding lugs 12. Secured to the backs of these socket members 13 are leaf springs 14 which are alternately engageable with the flat vertical and horizontal faces 15 and 16 respectively of the lugs 12, hence the bows 10 may be yieldably retained in either raised or lowered positions. If desired, an additional coil spring 17 may be employed for yieldably holding the bows in adjusted positions. As shown, this spring 17 is preferably sleeved upon a rod 18 within a tubular casing 19. One end of the rod 18 is secured to a bow 10 and is provided at its opposite end with the casing with a washer 20 that constitutes an abutment for one end of the spring 17, while the casing 19 has a closed end 21 constituting an abutment for the opposite end of the spring and has the other end thereof secured to the adjacent bar 9. In order that all of the bows 10 will move simultaneously I have provided a bar 22 that extends across the curved upper ends of the bow and is pivotally secured thereto by means of substantially U-shaped clips 23. As shown particularly in Figure 13, these clips 23 embrace the curved portions of the bows 10 and are terminally secured to the bar 22. Moreover the socket members 13 at one side of the aisle 6 are provided with depending arms or extensions 24 that are pivotally connected at their lower ends to a rod 25 extending longitudinally of the aisle. Preferably a link 26 is pivotally connected at its forward end to the rear end of this rod 25 and is pivotally connected at its rear end to the upper end of a bell crank lever 27. As shown in Figure 7, this lever 27 is pivoted intermediate its ends upon a suitable bracket 28 secured to the top section 5 and is provided at its lower end with a handle 29. A loop handle 30 is secured to the rear bow 10 and may be employed for pulling all of the bows simultaneously to lowered position, while the lever 27 may be used to raise all of the bows simultaneously to upright position, the springs 14 and 17 respectively serving to yieldably maintain the same in such adjusted positions.

Extending over the bows 10 and bar 22, is a covering 32, preferably of flexible material such as canvas. As shown, the intermediate portion 32' of this covering is slidably connected at the median line thereof by the tabs 33 and lacing 34 to the bar 22 of the supporting frame, while the longitudinal marginal portions 32" of the covering are firmly secured at their lower edges to the top sections

4 and 5, respectively, adjacent the attaching bars 9. Thus when the frame 8 is collapsed, the bows 10 will swing rearwardly and downwardly, whereas the portion 32' of the covering will move rectilinearly. In this connection it will be noted that these bows are spaced relatively far apart so that the canvas would have a tendency to stay between the bows when raised and, therefore, would have a tendency to bulge up when lowered. However this is prevented by the provision of an auxiliary lattice frame formed of light spring metal bars 36 and 37 respectively that are secured to the inner face of the canvas covering 32 and that tends to flatten the covering evenly upon the top sections 4 and 5 and bows 10 when the latter are in lowered position. As shown in Figure 3, the longitudinally extending bars 37 are preferably disposed at the sides of the cover 32 and extend through and slidably engage spaced elongated pockets 38 on the inner face of the canvas, while the cross bars 36 extend through similar transversely extending pockets 39 and are terminally secured to the longitudinally extending bars 37. Inasmuch as these bars 36 and 37 respectively are formed of spring metal and are carried by the canvas covering 32 which in turn is disposed over the bows 10 and bar 22 and is secured to the top sections 4 and 5, it is apparent that the cross bars 36 will bend over the bar 22 into inverted U-form when the bows 10 are raised and will straighten out on the bar 22 and bows 10 when the latter are lowered. Thus the canvas covering 32 will be stiffened to maintain straight lines when raised and will be flattened snugly and evenly upon the top sections 4 and 5 when lowered.

As shown in Figure 1, the forward end of the cover 7 is closed by a sheet 40 of canvas that is preferably secured to the forward bow 10 and to the top sections 4 and 5 respectively. Thus, when the cover is lowered the sheet closure 40 will move rearwardly and downwardly with the forward bow 10, likewise when the cover is raised the closure 40 will move upwardly and forwardly with said bow.

While it is believed that from the foregoing description, the nature and advantages of my invention will be readily apparent, I desire to have it understood that I do not limit myself to what is herein shown and described and that such changes may be resorted to when desired as fall within the scope of what is claimed.

What I claim as my invention is:

1. The combination with a motor bus having an upper deck provided with an open aisle, and top sections at each side of said aisle, of a collapsible cover for said aisle including a plurality of bows extending transversely of said aisle and having the leg portions thereof pivoted on said top sections, a flexible covering for said bows, stiffening

means for said covering including bars extending longitudinally of said covering, and means for flattening said covering on said bows when the cover is collapsed including 5 bars extending transversely of the covering and secured to the bars aforesaid.

2. The combination with a motor bus having an upper deck provided with an open aisle and top sections at each side of said aisle, of a 10 collapsible inverted trough-shaped cover for said aisle including a plurality of bows extending transversely of said aisle and having leg portions pivoted on said top sections, a bar carried by said bows at approximately 15 the median line thereof, a flexible covering for said bows and bar secured to said top sections, and yieldable bars adapted to be bent by the covering over the bar aforesaid into inverted U-form when the cover is raised and 20 adapted to flatten said covering on said bows when the cover is collapsed.

3. The combination with a motor bus having an upper deck provided with an open aisle, of a cover for said aisle including a plurality 25 of pivotally mounted bows extending transversely of said aisle and having depending extensions below their pivots, a rod connected to said extensions, and means for actuating said bows including a part pivotally 30 connected to said rod.

4. The combination with a motor bus having an upper deck provided with an open aisle, of a cover for said aisle including a plurality 35 of pivotally mounted bows having depending extensions at one side of said aisle, a rod connected to said extensions, a link connected to said rod, and a bell crank lever for 40 actuating said link.

5. The combination with a motor bus having an upper deck provided with an open aisle, and top sections at each side of said aisle, of a plurality of bows extending transversely of said aisle and having the leg portions thereof pivotally mounted on said top 45 sections, the leg portions on one top section having depending extensions, a rod connected to said extensions, and means for actuating said bows including a bell crank lever pivoted on one of said top sections, and a link terminally connected to said lever and rod.

6. The combination with a motor bus having an upper deck provided with an open aisle, and top sections at each side of said aisle, of a plurality of bows extending transversely 55 of said aisle and having the leg portions thereof pivotally mounted on said top sections, the leg portions on one top section having depending extensions, a rod connected to said extensions, and means carried by one 60 of said top sections and connected to said extensions for actuating all of said bows simultaneously.

7. The combination with a motor bus having an upper deck provided with an open 65 aisle, and top sections at each side of the

aisle, of brackets mounted on said top sections having portions extending at substantially right angles to each other, socket members pivotally connected to said brackets, bows extending transversely of said aisle having 70 their lower ends secured to said socket members, and means for retaining said bows in certain positions including leaf springs carried by said socket members alternately engageable with the portions aforesaid of 75 said brackets.

8. The combination with a motor bus having an upper deck provided with an open aisle, and top sections at each side of the aisle, of a cover for said aisle including a plurality 80 of bows extending transversely of said aisle, brackets mounted on said top sections, socket members pivotally connected to said brackets and receiving the lower ends of said bows, certain of said last mentioned 85 members formed with depending extensions, and a rod connected to said extensions for actuating each of said bows simultaneously.

9. The combination with a motor bus having an upper deck provided with an open aisle, and longitudinally extending top sections at each side of said aisle, of a plurality 90 of bows having the leg portions thereof pivotally mounted on said top sections, a covering for said bows comprising a strip of flexible 95 material having its longitudinal marginal portions secured to said top sections and having its longitudinally extending portions on the intermediate arched portions of said bows, and a lattice frame pivotally connected 100 to the intermediate portions of said bows and having resilient means for maintaining substantially straight lines in the covering when said bows are upright and for flattening out said covering on said top sections when said 105 bows are lowered.

10. The combination with a motor bus having an upper deck provided with an open aisle, and longitudinally extending top sections at each side of said aisle, of a covering 110 of flexible material movable rectilinearly above said aisle, and supporting means for said covering including a lattice frame slidably connected to said covering, and a plurality of bows having the leg portions thereof 115 pivotally connected to said top portions, and having the intermediate loop portions thereof pivotally connected to said lattice frame.

11. The combination with a motor bus having an upper deck provided with an open aisle and longitudinally extending top sections at each side of said aisle, of a covering for said aisle comprising a strip of flexible material having its longitudinal edges rigidly secured to said top sections adjacent to said aisle, and a collapsible supporting frame for said covering including yieldable members slidably connected to said covering and mounted to move longitudinally of said aisle, 125 130

and a plurality of bows mounted on said top sections and carrying said members.

12. The combination with a motor bus having an upper deck provided with an open aisle, and top sections at each side of said aisle, of a cover for said aisle including bows extending transversely of the aisle having the leg portions thereof pivoted on said top sections and having depending extensions below their pivots, means for actuating said bows including a bar connected to said extensions, and yieldable means on said top sections and engageable with said bows for retaining the same in certain positions with respect to said top sections.

15. In testimony whereof I affix my signature.

DANIEL N. HYMAN.
